Fig. 2

Fig. 3

FIG. 1 is an enlarged fragmentary top plan view of a plate or similar article of conventional configuration showing my new design, with a repeat unit being shown between the dashed lines;

FIG. 2 is a further enlarged fragmental sectional view of the design taken along line 2—2 of FIG. 1; and

FIG. 3 is a plan view of the entire plate or similar article of FIG. 1, it being understood that the ornamentation shown within the dashed line sector is continued about the entire surface of the plate in the path indicated.

I claim:

The ornamental design for a plate or similar article, as shown and described.
